UNITED STATES PATENT OFFICE

154,196

DESIGN FOR A DECANTER

Jesse H. Clark and Harper Richards, Chicago, Ill.,
assignors to Cory Corporation, Chicago, Ill. a
corporation of Delaware

Application July 26, 1947, Serial No. 140,534

Term of patent 3½ years

(Cl. D44—21)

To all whom it may concern:

Be it known that we, Jesse H. Clark and Harper Richards, both citizens of the United States, residing at Chicago, in the county of Cook and State of Illinois, have invented a new, original, and ornamental Design for a Decanter, of which the following is a specification, reference being had to the accompanying drawing, forming part thereof, wherein

Figure 1 is a perspective view of a Decanter, showing our new design; and

Fig. 2 is a fragmentary side elevational view of the bottom portion of the decanter.

We claim:

The ornamental design for a decanter, as shown.

JESSE H. CLARK.
HARPER RICHARDS.
